MOP

Warren G. Bailey, Evanston, Ill., assignor, by
mesne assignments, to Reconstruction Finance
Corporation, Chicago, Ill., a corporation

Application May 13, 1937, Serial No. 142,463

2 Claims. (Cl. 306—19)

This invention relates to a mop, and more particularly to a floor mop of the type commonly used to remove dust, etc. from hardwood floors and other surfaces.

5 An object of the invention is to provide a floor mop having improved means for connecting the handle with the frame or base plate of the mop.

Another object is to provide a mop in which the handle is frictionally held against change of 10 its angular position through resilient engaging means. A further object is to provide a mop in which the handle is neatly secured to the base frame and in which the handle is permitted to move downwardly to an extremely low rearward 15 position.

Another object is to provide a mop of simple construction which is strong and secure.

The invention is illustrated in a preferred embodiment by the accompanying drawings, in 20 which—

Fig. 1 is a plan view of the improved mop, the handle coupling being shown in raised position; Fig. 2, a longitudinal sectional view taken as indicated at line 2 of Fig. 1, the handle coupling being shown in the same position as in 25 Fig. 1; Fig. 3, a broken sectional view of the base frame and coupling, this view being somewhat similar to Fig. 2, but showing the coupling in its extreme lower position; Fig. 4, a transverse sectional view taken as indicated at line 4 of Fig. 3; Fig. 5, a detail sectional view of the top plate at the pivoted connection, the section being taken as in Fig. 4; and Fig. 6, an illustrative view 30 of the coupling piece before it is formed into shape.

As illustrated, A designates a frame or base plate; B, a handle coupling member; and C, a swab.

The base plate A comprises a piece of sheet 40 metal of the general shape shown in Fig. 1 and having a substantially flat central portion 10. The outer edges of plate A are turned downwardly to form a substantially vertical edge portion 11 to which the swab C may be attached. 45 At spaced intervals edge 11 is provided with elongated apertures 12 through which brads or fasteners may extend.

The swab C comprises a great many strands of flexible fibrous material 13 which is gathered 50 and held within the fabric strip 14. It is understood that the swab may be constructed in any suitable way and may be made of any desired materials. In attaching the swab to the base plate A, I prefer to use the split brads or fasteners 15. These brads may be passed through

fabric 14 and inserted through apertures 12 in edge 11 and then may be spread apart at their points to secure the swab in place. Preferably, the brads 15 are of the flat type and when inserted through elongated apertures 12 will not turn within the aperture. Also, the flat fasteners bend over easily at their points and provide a maximum of security.

Inward of its edge, plate A is provided with a groove 16 which extends completely about the 10 plate parallel with the edge. At spaced intervals along this groove are the apertures 17 through the bottom of the groove. The purpose of groove 16 and apertures 17 therein is to enable oil to be poured into the grooves and drained down into 15 material 13 through the apertures, spreading itself evenly through the material. The use of such a groove for this purpose is well known, and this particular feature is not a part of my invention.

Located centrally of plate A are two spaced 20 slots 18 extending in parallel relation longitudinally of the plate. Adjacent the outer edges of slots 18 the metal of the plate is struck upwardly to form sockets 19 opening on the underside of the plate. The interior surface of sockets 19 is 25 formed so as to snugly receive the end portion of a cylindrical pin. Adjacent the inner edges of slots 18 and extending between these slots the metal of plate A is struck downwardly to form a rather shallow groove 20 having a rounded 30 bottom. Fig. 5 of the drawings shows more clearly the structure of the base plate when it is prepared for connection with the coupling member.

Coupling member B may be formed from a 35 sheet of metal as illustrated in Fig. 6 of the drawings. By suitable stamping and forming operations the ends 21 and 22 of this sheet are brought together and the piece given a shape as illustrated in Figs. 1 to 3. The holding ring 23 40 may be placed about the upper end of the coupling to keep it from spreading.

As thus formed, coupling B has an upper tubular portion 24 which is provided with the internal ridges 25 which serve as screw threads for engaging complementary threads on the end portion of a handle. The bottom 29 of tubular portion 24 is rounded and below this are the fins 26 which extend laterally to each side and downwardly to the bearing portion 27 which is in the 45 form of a partial cylinder. On both front and rear of the coupling are the reinforcing ribs 28 which extend from bottom 29 of the tubular portion to the middle of bearing portion 27.

A pin 30 is received through the interior of 55

bearing portion 27 and has its ends disposed within sockets 19. When thus placed the pin 30 serves as a pivot about which the coupling member may turn in angular movement. It will be apparent 5 that pin 30 can not be inserted to the position just described without deforming the shape of the plate A to some extent. In inserting the pin one of several methods may be used. For example, the pin may be placed within bearing portion 27 10 and one end pushed laterally beyond the end of the pin socket; then the other end of the pin may be brought into register with the other of the pin sockets, and the pin finally pushed back endwise into proper position.

15 The metal of base plate A between grooves 18, crimped as it is to form the slight rounded groove 20, provides a resilient cushion against which the bearing portion may rest. When the pin is inserted as above described, this strip of metal is 20 temporarily deformed to allow the pin end to be extended beyond its socket. And after the pin is inserted and the connection between the coupling and the base plate completed, this metal between 25 slots 18 bears resiliently against the exterior of the cylindrical bearing portion of the coupling and maintains constant frictional engagement between the base plate and the coupling. Such a frictional engagement serves to hold the coupling member in one angular position until the mop 30 handle is moved to cause this position to be changed.

Base plate A is provided with an opening 31 rearward of the rounded groove. This opening has a central enlarged portion 31^a into which is 35 received the lower part 29 of the tubular portion of coupling B when this coupling is moved rearwardly into lowered position. Rearward of enlarged portion 31^a opening 31 is of substantially elliptical form as indicated at 31^b of Fig. 1. The 40 forward portion 31^c of the opening is in the form of a relatively narrow neck which is adapted to receive the rib 28 when the coupling is moved rearwardly into lowered position.

It will be observed that the person using the 45 improved mop may lower the handle to a very low position for dusting floors under beds, dressers, and other pieces of furniture, and at the same time may have the advantage of a handle pivoted in the base plate. This construction of the pivoted joint is very neat in appearance and well 50 balanced. The awkwardness of any upwardly extending pivot carrying arms is herein eliminated without sacrificing freedom of handle movement.

55 The base plate A is normally held in its angular relation to the handle, so that when the mop is raised and lowered to and from the floor the mop can not turn or flop about. Also it will

readily appear that as the mop handle is moved forwardly to its extreme position, as shown in Figs. 1 and 2, the tubular portion 24 is not allowed to strike against and mar the top surface of the plate. The rib 28 first engages the plate adjacent 5 groove 20 and prevents the upper portion of the coupling from coming into contact with the plate.

It is understood that the construction of the mop may be varied in many details from the specific construction described without departing from the spirit of the invention. For example, the slots 18 may be lengthened to provide added flexibility, or the ends of pin 30 may be hexagonal or other shapes with sockets 19 of corresponding shapes. 10 15

The foregoing detailed description has been given for clearness of understanding only, and no unnecessary limitations should be understood therefrom, but the appended claims should be construed as broadly as permissible, in view of the 20 prior art.

I claim:

1. In a floor mop of the character set forth, a base plate of the shape indicated and having depending side flanges, said base plate having a pair of spaced slots, the metal between the slots being sprung downwardly and the metal to the side of the slots being pressed upwardly to afford end sockets for a pin, and a third slot in said base plate extending between said pair of slots and 25 overlapping the same, said three slots providing between them two relatively narrow spring bands affording a spring base, a pivot pin resiliently supported within said spring base and having its ends engaging said sockets, and a mop handle provided with a pivot socket extending substantially 30 the distance between said slots and receiving said pivot pin, said handle socket being resiliently gripped by said spring base so as to maintain said handle socket in any desired angular position. 35 40

2. In a floor mop of the character set forth, a base plate formed of spring metal and having downwardly extending marginal flanges, said base plate being provided with a pair of spaced slots which are co-extensive with a third slot extending 45 between said pair of slots in overlapping relation, said slots providing between them narrow flexing bands affording a resilient pin base, the metal extending laterally of said pair of slots and being pressed upwardly to provide pin sockets, a pin 50 received within said spring base and having its ends received within said sockets, and a handle socket having a wide front flange bent back upon itself to provide a receiving socket for said pin, said flexing bands engaging said socket so as to maintain said socket in any desired angular position. 55

WARREN G. BAILEY.
